UNITED STATES PATENT OFFICE.

NEHEMIAH HAYDEN, OF ESSEX, CONNECTICUT.

DESIGN FOR COFFIN-HANDLE EARS.

Specification forming part of Design No. 6,228, dated October 29, 1872.

To all whom it may concern:

Be it known that I, NEHEMIAH HAYDEN, of Essex, in the county of Middlesex and State of Connecticut, have invented a new and original Design for Coffin-Handle Ears, of which the following is a specification:

The nature of my design is fully represented in the accompanying photographic illustration, to which reference is made.

A is the coffin-handle. B is the ear to which the same is attached, and which is secured to the coffin by screws in the usual manner.

The surface of the ear B may be ornament-

ed with figures of any design selected; but extending from the ear B are the head and wings C D, representing the figure of an angel. This figure of an angel constitutes the distinctive character of my design; and

I accordingly claim as my invention—

The design for coffin-handle ears, substantially as shown and described.

NEHEMIAH HAYDEN.
